UNITED STATES PATENT OFFICE.

PETER NILSON, OF PHILADELPHIA, PENNSYLVANIA.

IMPROVEMENT IN TILTING CHAIRS.

Specification forming part of Letters Patent No. 177,350, dated May 16, 1876; application filed September 18, 1875.

To all whom it may concern:

Be it known that I, PETER NILSON, of Philadelphia, in the county of Philadelphia and State of Pennsylvania, have invented certain new and useful Improvements in Tilting Chairs; and I do hereby declare the following to be a full, clear, and exact description of the invention, such as will enable others skilled in the art to which it pertains to make and use it, reference being had to the accompanying drawings, which form part of this specification, in which—

Figure 1 is a vertical section of my invention. Fig. 2 is a plan, with the upper part of the chair removed.

My improvements have reference particularly to the spider and spring by which the tilting of the chair-seat is facilitated. They have, also, reference to means for locking the seat so as to render it rigid when it is desired to avoid tilting.

A, in the accompanying drawing, represents a chair-seat, and B B the legs, sustaining a screw, b, on which is supported a spider, C. The spider C has two lateral arms, c c, transverse to which are two other arms, c¹ and c². The arms c c have bearings in lugs or boxes a a, affixed to the under side of the seat A, enabling the seat to be rocked or tilted in the customary manner. The arm c¹ curves upwardly, so as to meet the chair-seat A when the latter is in a horizontal position, while the arm c² has a reverse downward curve. D is the spring, having ends D¹ and D², bent toward each other. This spring is secured to the arm c¹ by the loop d, adjustable thereon by means of a set-screw, d¹, and to the chair-seat A by a bracket, a'. E represents a yoke, and e an adjusting-screw connecting the ends d² d³ of the spring D, and affording means for varying the tension or stiffness of said spring according to the weight of the occupant of the chair. This yoke and adjusting-screw may be wholly dispensed with, if desired, not being absolutely necessary, except for the purpose indicated. The stiffness of the spring may be also varied by moving the loop d nearer to or farther from the screw b. If desired, the spring

may be strengthened by the addition of one or more supplementary leaves, the forward extremity thereof extending far enough only to find a bearing under the loop d, and not curving upward sufficiently to meet the end d². c³ represent short arms, extending backwardly from the arms c c of the spider C, and designed to operate as guards and prevent the spring D from being depressed too far, which would be likely to occur in case said spring were adjusted to suit a light body, and a heavy person should take the chair. F represents a button, pivoted to the chair seat A by means of a screw, f, turning freely on the neck thereon. When said button is turned as shown in Fig. 1, it engages with the forward extremity of the arm c¹, holding the latter in close contact with the seat A, and preventing said seat from being tilted. When turned to one side or around, as shown in dotted lines in said figure, the button does not engage with the arm c¹, and the seat may then be tilted at will. This locking and unlocking of the seat may be readily accomplished by the occupant of the chair without rising from his position.

What I claim is—

1. The spider C, having lateral arms c c and arms c¹ c² transverse thereto, the arm c¹ curving upwardly to meet the chair-seat, and the arm c² having a reverse downward curve, substantially as shown and described.

2. The spring D, secured to the spider C in advance of the center of the latter, and to the chair-seat A in rear of the central line of said seat.

3. The spring D, having curved ends D¹ and D², united by a yoke or equivalent means, substantially as set forth.

4. In combination with the curved spring D, the yoke E, and adjusting-screw e, substantially as shown and set forth.

In testimony that I claim the foregoing I have hereunto set my hand this 25th day of August, 1875.

PETER NILSON.
